THREADING BLOCK TOY

Lynn Pressman, 200 5th Ave., New York, N.Y. 10017

Filed Sept. 18, 1970, Ser. No. 25,052

Term of patent 14 years

Int. Cl. D21—01

U.S. Cl. D34—15

FIG. 1 is a perspective view of a threading block toy embodying my new design;

FIG. 2 is a front elevational view thereof, the rear being similar;

FIG. 3 is an inverted side elevational view thereof, the other side being similar;

FIG. 4 is a top plan view thereof; and,

FIG. 5 is a bottom plan view thereof.

The tether is shown fragmentarily in FIGS. 2 through 5 for convenience of illustration.

I claim:

The ornamental design for a threading block toy, as shown and described.
